US0D1068315S

(12) United States Design Patent (10) Patent No.: US D1,068,315 S
(45) Date of Patent: * Apr. 1, 2025

(54) TRAY

(71) Applicant: Junren Huang, Fujian Province (CN)

(72) Inventor: Junren Huang, Fujian Province (CN)

() Term: 15 Years

(21) Appl. No.: 29/963,174

(22) Filed: Sep. 16, 2024

(51) LOC (15) Cl. 06-04

(52) U.S. Cl.

USPC D6/524

(58) Field of Classification Search

USPC ..... D6/524, 551, 525, 536-537, 540, 566, D6/567, 320, 515, 518; D3/302, 304, D3/307; D7/354, 357, 677, 359, 541, D7/555, 615; D8/80, 83, 94, 107, 300; D32/40, 42, 46, 49, 51, 52; D34/10 CPC .
